(No Model.)

S. P. LERCH.
MITER BOX.

No. 562,471.

Patented June 23, 1896.

UNITED STATES PATENT OFFICE.

SAMUEL P. LERCH, OF CANTON, OHIO.

MITER-BOX.

SPECIFICATION forming part of Letters Patent No. 562,471, dated June 23, 1896.

Application filed March 12, 1896. Serial No. 582,954. (No model.)

To all whom it may concern:

Be it known that I, SAMUEL P. LERCH, a citizen of the United States, residing at Canton, in the county of Stark and State of Ohio, have invented certain new and useful Improvements in Miter-Boxes; and I do hereby declare that the following is a full, clear, and exact description of the same, reference being had to the annexed drawings, making a part of this specification, and to the letters of reference marked thereon, in which—

Figure 1 is a perspective view showing the different parts properly assembled. Fig. 2 is a vertical section showing a portion of the vertically-adjustable shaft and the transverse section of the upper cross-bar, also showing the position of the ball-bearings. Fig. 3 is a transverse section of one arm of the saw-guides. Fig. 4 is a detached view showing the bottom or lower portion of one of the saw-guides. Fig. 5 is a view showing a portion of the vertically-adjustable shaft, also showing the disk through which said shaft is passed and device for holding the saw-guide at the desired angle. Fig. 6 is a vertical section of the adjustable shaft and its disk.

The present invention has relation to miter-boxes; and it consists in the different parts and combination of parts hereinafter described, and particularly pointed out in the claims.

Similar letters of reference indicate corresponding parts in all the figures of the drawings.

In the accompanying drawings, A represents the base or bed, which may be constructed in the ordinary manner and is provided with the usual right-angled flange a, said flange being provided with the opening b, or, if desired, two flanges may be attached to the bed A, said flanges being separated a short distance apart. To the right-angled flange a are attached the short posts B, to which posts are detachably connected the posts or standards B', by means of the pins b' or their equivalents. The top or upper ends of the posts or standards B' are held in proper position with reference to each other by means of the cross-bar c, which cross-bar is detachably connected to the top or upper ends of the posts or standards B' by means of the pins b². The cross-

bar c is provided with the aperture c', through which aperture the vertically-adjustable shaft or bar C is passed, said shaft being located and arranged substantially as shown in Fig. 1. To the bottom or lower portion of the shaft C are attached the saw-guides D, which saw-guides may be of the form shown in Fig. 1, and are clamped together by means of the clamping-bolts d, which clamping-bolts are located as illustrated in Fig. 1. The bottom or lower ends of the saw-guides D are provided with the integral plates d', which plates are provided with suitable recesses to receive the balls d², which recesses form suitable sockets for said balls.

It will be understood that when the saw-guides D are placed together, as illustrated in Figs. 1 and 3, the balls d² cannot become detached from their sockets, but at the same time a sufficient amount of the surfaces of said balls will be exposed to form suitable bearings and guides for the saw.

In Fig. 3 I have illustrated a back-saw placed between the guide-arms, and for the purpose of providing bearings for the under edges of the back e of the saw the balls f are provided, and are located substantially as shown in Fig. 4. It will be understood that balls, such as f, are to be placed in the opposite guide, as illustrated in Fig. 3.

To the posts B' is attached the sliding bar E, which sliding bar is provided with the flanged disk F, which flanged disk is provided with a series of notches g, said notches being located and arranged substantially as shown in Figs. 1 and 5, and are for the purpose hereinafter described. Between the saw-guides D is located the bar G, the bottom or lower end of which is provided with the head g', said head being for the purpose of preventing any upward movement of the bar G. The bar G is provided with the arms h, which arms carry the sliding pin h' and hold said pin in a vertical position. The bottom or lower end of the pin h' is formed so as to fit into any of the notches g, and thereby hold the saw-guides D at the desired point of angularity. When it is desired to change the angularity of the saw-guides D, the pin h' is elevated, thereby allowing the saw-guides to be turned at an angle with reference to the

bed A. The shaft C is provided with the collar k, which collar is located above the cross-bar c, and when it is desired to cut with the saw to any desired depth, that is, one inch or 5 two, the collar k is adjusted upward the distance the saw is to cut, after which the saw is placed in position, or if desired the saw may be in position after the collar is adjusted, as it is immaterial at which time the 10 collar k is adjusted. As the saw descends or cuts its way into the wood, the saw-guides D will follow the downward movement of the saw until the collar k comes in contact with the upper side of the cross-bar, thereby limiting the downward movement of the saw-guide and gaging the depth of the kerf to be cut. For the purpose of providing an easy 15 movement for the shaft C, said shaft is provided with the grooves k², which grooves are 20 for the purpose of receiving the ball-bearings k³, as illustrated in Fig. 2, said ball-bearings being located in proper recesses or 25 sockets formed in the cross-bar c.

It will be understood that the shaft C is to 25 be provided with a scale showing the number of inches and fraction of inches, so as to provide an easy and convenient means for adjusting the collar k. It will be understood 30 that as the saw descends the shaft C, together with the saw-guides D, and the bar E, with its adjustment, follow the downward movement of the saw, thereby holding the saw in a true vertical position until the saw has 35 fully entered the timber, and in instances where the saw is not to be entered its entire width the guides will at all times be in proper position to hold the saw in a true vertical position and at the desired angle to the bed A.

For the purpose of providing a miter-box 40 that can be easily transported or placed in a tool-chest, the posts or standards B' are removably connected to the posts B, and the cross-bar c is also removably attached to the top or upper ends of said posts, thereby providing 45 means for removing the cross-bar c, after which the shaft C, together with its attachments, can be removed, thereby providing a knockdown miter-box.

The bottom or lower end of the shaft C is 50 provided with the groove H, which groove receives the inner end of the set-screw II', as shown in Fig. 6, thereby allowing the saw-guides D to be turned upon the shaft C, and if desired said set-screw can be turned sufficiently 55 to tighten the saw-guides and prevent them from turning upon the shaft C; but this is not essential, inasmuch as the guide-arms are held by means of the pin h'. For the purpose of securely connecting the cross-bar E and its disk F to the lower portion of the shaft C, the disk F is provided with the integral collar II², through which collar is placed the set-screw II³.

For the purpose of normally holding the 65 pin h' in the desired notch g, the spring h² is

provided and is located around the pin h', as illustrated in the drawings.

The balls f, located in the guides D, are so arranged that the bottom or under edges of the back rib of the saw will rest or ride on said 70 balls.

Having fully described my invention, what I claim as new, and desire to secure by Letters Patent, is—

1. The combination of the bed A, provided 75 with the right-angled flange a, the posts B, connected to the flange, the detachable posts or standards B', the detachable cross-bar c, connected to the top or upper end of the posts or standards B', and provided with the balls 80 k³, the shaft C, provided with the longitudinal grooves k², the sliding cross-bar E, connected to the bottom or lower portion of the shaft C, and provided with the notched disk F, the bar G, provided with the arms h, the pin h' and the spring h², located around said pin and between the arms h, and the saw-guides D, pivotally connected to the bottom or lower end of the shaft C, substantially as 85 and for the purpose specified. 90

2. The combination of a vertically-adjustable scaled shaft provided with longitudinal grooves, the cross-bar c, provided with the balls k³, the saw-guides pivotally connected to the bottom or lower end of the shaft C, and 95 the sliding bar E, provided with the notched disk F, and means for holding said guide-arms at the desired point of angularity, substantially as and for the purpose specified.

3. In a miter-box, the combination of a bed 100 provided with a right-angled flange, posts or standards secured to the right-angled flange, a sliding bar provided with a notched disk, the bar G, provided with the arms h, the pin h' and the spring h², the shaft C, provided 105 with an adjustable collar, the cross-bar c, and the vertically-adjustable pivoted saw-guides D, substantially as and for the purpose specified.

4. In a miter-box, the combination of a bed 110 provided with posts or standards, cross-bars connected to said posts or standards, a vertically-adjustable shaft provided with saw-guides, having the balls f, and d², the balls f located to receive the lower edges of the back 115 rib of the saw, substantially as and for the purpose specified.

5. In a miter-box, the combination of a scaled shaft, vertically adjustable and provided with the longitudinal grooves, the balls 120 k³, and the adjustable cross-bar c, substantially as and for the purpose specified.

In testimony that I claim the above I have hereunto subscribed my name in the presence of two witnesses.

SAMUEL P. LERCH.
